UNITED STATES PATENT OFFICE.

SHERMAN E. BAUGHMAN, OF TAYLORVILLE, ILLINOIS.

WAGON-BED FASTENER.

SPECIFICATION forming part of Letters Patent No. 388,809, dated September 4, 1888.

Application filed December 20, 1887. Serial No. 258,422. (No model.)

To all whom it may concern:

Be it known that I, SHERMAN E. BAUGHMAN, of the city of Taylorville, county of Christian, and State of Illinois, have invented 5 a certain new and useful Device for Detachable Securing Wagon-Beds to the Running-Gear, of which the following is a specification.

Wagon-beds are worn to a disproportionate 10 extent over the axles, particularly the rear axle; and it is the object of my invention to remove the cause of the wear by securing the bed to the bolster in such manner that there shall be no independent motion in the bed. 15 I accomplish this object and at the same time permit the bed to be readily removed from the running-gear by means of the device herein-after set forth and claimed.

In the drawings accompanying and forming 20 a part of this specification, Figure 1 represents, by broken lines, a bolster and bed, and shows in solid lines my device applied thereto. Fig. 2 is a central vertical section of the tension-regulating mechanism. Fig. 3 is a face 25 view of the wrench. Fig. 4 is a central vertical section of a retaining-hook.

Angle-bracket *a a'* is secured to the bed adjacent to the bolster by means of bolts *b b*. Lug *c* projects downward from the bracket *a* 30 *a'*, and is perforated to receive rod *f*. Encircling rod *f*, on the outer side of lug *c*, is washer *n*, (seen in Fig. 2,) and embracing the washer is wrench *d*. Screwed onto the threaded termination of rod *f* is octagonal nut *e*, which 35 imparts tension to said rod by pressing against washer *n*, and through the washer against lug *c*. Angle-bracket *k k'* is secured to the opposite side of the bed by bolts *l l*, and has downward-extending lug *m*, with which rod *f'* is 40 connected. Rods *f* and *f'* are connected at the center of the bolster and form a continuous line. Plates *g*, carrying hooks *h*, are secured to the bolster at opposite ends and somewhat lower than the lugs of the brackets. 45 Pins *o*, as shown in Fig. 4, and screws *i*, as shown in Fig. 1, are used to secure the plates to the bolster. Rods *f f'* extend under hooks *h* in a right line, but bend upward at their ends to connect with the lugs of the brackets.

As nut *e* is tightened, the rods tend to assume 50 a right line between the lugs. This tendency is obstructed by hooks *h*, and in consequence both hooks and bolster are drawn toward the bed. Adjustment of nut *e* is effected by wrench *d*, which corresponds in size and shape 55 thereto, and said adjustment is accomplished by passing the wrench onto the nut, giving the nut a partial rotation in the desired direction, passing the wrench onto the washer and back to its original position, and proceeding 60 as before. The motion of the wrench is oscillatory, with a swing in one direction on the nut and a swing in the contrary direction on the washer.

The wrench may be used, as explained, in 65 close proximity to the bolster, and is constantly ready to be so used. After and before there is any strain on the rods the nut may be manipulated without the wrench; but in order to impart the necessary degree of tension the wrench is necessary.

To enable the bed to be removed from the running-gear, it is only necessary to loosen the nut until the rods are sufficiently slack to be passed from under the hooks.

The wrench from its position is readily accessible.

Having thus described my invention, I claim as new and desire to secure by Letters Patent—

1. In a device for securing beds to wagons, 8c a bracket system on the bed, a hook system on the bolster, a connecting-rod, and a tension-regulating device, all in combination, as and for the purpose set forth.

2. A device for securing beds to wagons, 85 comprising the brackets on opposite sides of the bed, hooks on the bolster, a rod connecting the brackets and engaging the hooks, and a tension-regulating device for the rod, as and for the purpose set forth.

3. A device for securing beds to wagons, comprising bracket *a a'*, having lug *c*, bracket *k k'*, having lug *m*, plates *g*, having hooks *h*, rod *f f'*, connected with lug *m*, passed under the hooks and through lug *c*, and nut *e*, screwed 95 onto the outer end of the rod, as and for the purpose set forth.

4. A device for securing beds to wagons,

comprising bracket $a a'$, having lug c , bracket $k k'$, having lug m , plates g , having hooks h , rods $f f'$, connected with lug m , passed under the hooks and through lug c , nut e , screwed onto the outer end of rod f , washer n between the nut and the lug, and wrench d , normally encircling the washer, as and for the purpose set forth.

In testimony whereof I sign my name in the presence of two subscribing witnesses.

SHERMAN E. BAUGHMAN.

Witnesses:

JOHN BAUGHMAN,
F. D. COFLIN.
